A file may also be attached to the device of Fig. 1, as shown in Fig. 11. Nut 36 is revolved to loosen clamping plate 37 and one end of a file 55 is inserted intermediate the clamping plate and the side wall 28. The nut 36 is then revolved to urge the clamping plate toward side wall 28 so that the file is firmly held against side wall 28 and base plate 21.

A saw blade 60 may also be combined with the device of Fig. 1 as a longitudinal extension thereof. The saw blade 60 is provided with a longitudinal slot 61 adjacent to and spaced inwardly from one end thereof and a transverse notch intermediate the one end and the slot 61. The saw blade 60 is inserted intermediate blade 38 and side wall 28 with the slot 61 receiving pivot pin 35. The notch 62 will then receive the stud 44 to hold blade 60 against rotation in one direction. This is sufficient for a sawing operation as force is only exerted against the toothed edge 63 of blade 60, which force is resisted by the stud 44.

Thus, it is seen that the versatile combination tool of Fig. 1 serves, in addition, as a handle attachment for a variety of other tools.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

In a tool holder, a handle construction comprising an elongated metal body having plane side and bottom walls, a shield plate having an elongated side portion with a flange extending along one longitudinal edge thereof, means to secure a saw blade having a T-slot at one end to the body, said means including a stud projecting from the side wall of the body adjacent one end thereof and a cooperating threaded pin and nut spaced from the stud, means pivotally securing the shield plate to the body in selective angular positions, said means being located at the end of the body opposite from said one end, whereby the free end of the flange on the shield can be positioned to engage the edge of a saw blade between a pair of adjacent teeth while the stud is received within one portion of the T-slot and the threaded pin is received within the other portion thereof to securely hold the blade to the handle.
